JAVELIN

Karl A. Schlademan and Urige Glenn Whiffen,
Pullman, Wash.

Application February 14, 1939, Serial No. 256,288

8 Claims. (Cl. 272—59)

Our invention relates to improvements in javelins and the like, and specifically to features in a javelin that permit the manufacture of a javelin which is easier to throw than the conventional article and is more resistant to shocks encountered in the sport, which shocks result in a high percentage of breakage.

It is well known by those associated with the sport of Javelin throwing that the use of relatively strong, durable wooden shafts for javelins has required the construction of a shaft that is relatively small in circumference. Conventional wood, such as ash, hickory, and birch, has been used in order to secure a strong, durable javelin and because such woods are characteristically dense, the shafts are cut very thin and tapering, with the result that when they are thrown they vibrate with a marked degree of flutter and when they strike the ground and are vibrating, they tend to destroy themselves with fractures, usually occurring at the point where the shaft enters the ferrule.

It has been conceived that the use of a softer, lighter wood would permit the construction of a javelin having a relatively large circumferential measurement more nearly adapted to fit, and to be gripped by the hand of the athlete. This would permit him to impart a twisting motion at the moment he throws the javelin, whereby the javelin spins or rifles during its passage through the air, striking the earth without the attendant vibration which, it is recognized, brakes the wood adjacent the ferrule at its tip.

The primary object of our invention is to provide a Javelin of a relatively large circumferential measurement that otherwise meets the requirements laid down by the directors of the sport of Javelin throwing; and one that is adapted to be more easily and skillfully thrown.

Another object of our invention has been to produce a Javelin having a lower percentage of breakage in use.

A still further object of our invention is to provide a Javelin which may be readily balanced to meet the various circumstances encountered due to lack of uniformity in the materials available.

Other objects and advantages of the invention will be apparent during the course of the following description.

In the accompanying drawing forming a part of this specification, and in which like numerals are employed to designate like parts throughout the same,

Figure 1 is a view in elevation of a Javelin of our construction;

Figure 2 is a longitudinal cross sectional view through a forward portion of our Javelin;

Figure 3 is a longitudinal cross sectional view through the central portion of our Javelin;

Figure 4 is a longitudinal cross sectional view through the trailing end of the Javelin;

Figure 5 is a vertical cross sectional view taken on lines 5—5 of Figure 3;

Figure 6 is a vertical cross sectional view taken on lines 6—6 of Figure 2;

Figure 7 is a vertical cross sectional view taken on lines 7—7 of Figure 3;

Figure 8 is a vertical cross sectional view taken on lines 8—8 of Figure 2; and

Figure 9 is a longitudinal cross sectional view through a portion of the Javelin adjacent the hand grip.

Referring to the drawing, Figure 1 illustrates a Javelin whose shaft 1 is tapered at its forward end 2 for the reception of a ferrule point 3 and which also has a tapered trailing end 4 and a wrapped handle or grip 5. The shaft 1 is formed of a pair of long, relatively thin strips of wood 6 and 7 having longitudinal grooves 8 and 9 cut into one face of each of them. The forward end of this shaft 1 is provided with tapered laminated splints 10 and 11 for a purpose to be later described.

Fitted to the forward end of the shaft 1 is the ferrule point 3 having an interior tapered bore 4 for the reception of the forward end of the wooden shaft. A relatively sharp impact point 12 is provided on this member 3. The hand or grip 5 is of the usual construction and consists in helical wrappings of cordage 13 begun and terminated in the usual manner of such wrappings.

The adjoining grooves 8 and 9 extend throughout the length of the Javelin from a point a short distance back from the leading end to a point short of the trailing end. A counterweight 14 may be placed in any required location between the shaft halves 6 and 7 to properly balance the Javelin.

Referring to Figure 9 the shaft halves 6', 7' are shown to have a slightly greater degree of taper to the point 15 forming a larger diameter which is abruptly reduced to the normal size and the usual hand grip 5 of wrapped cordage 13 is provided of normal size. The result is a streamline effect to enhance the possibilities of gaining distance when thrown.

To construct a Javelin embodying the features of our invention we take substantially square

pieces of a wood commonly known as Alaska cedar and of sufficient length to meet the requirements for a regulation javelin. This piece is split longitudinally in half. We do not wish to be limited in practicing our invention to the use of Alaska cedar but mention that wood specifically because it meets our requirement for a tough-fibered, light weight wood, its use mentioned herein being merely illustrative. Any wood having similar characteristics, by whatever name it may be called, would be suitable.

The split pieces of the original stock are at all times paired together for use in the final construction of a unitary javelin. One of said pieces is turned end for end with relation to the other and with the result that a reversing of the grain is accomplished to increase strength and rigidity. The two rectangular pieces split from the square section with which we started are now formed or provided with dado grooves 8 and 9 which we have shown in the drawing to be square-cut but which, of course, could be round or of any other shape practical to produce. These two grooves are cut in such a manner that when the rectangular strips are joined together the grooves join and form a single longitudinal opening throughout the length of the javelin from a point just back of the tip to a point short of the trailing end. At this time a suitable counterweight 14 of metal or of more dense wood may be fitted and fixed into the interior of the trailing end of the javelin according to the requirements for balance as observed at this stage of the operation. When the proper balance is obtained and the grooving has been accomplished, the two rectangular strips are glued together and form the blank from which the finished javelin is to be formed. Under certain circumstances and in order to properly strengthen the forward end of the javelin at a point adjacent its attachment of the ferrule point, the outer surfaces of the rectangular strips are planed or otherwise dressed away to form rather abrupt tapers and splints or laminations 10, 11 are glued thereon in a suitable manner.

The next step in shaping our javelin consists in cutting away surplus material to the end that the desired round and tapered shape results. Due to variances in woods and other requirements, the shaping of the javelin may vary slightly but all the time is to be kept as close to the conventional as possible. Because of our use of the lighter, tough-fibered wood than is conventional, we are permitted to leave intact considerably more material in the central portion of the javelin, thus permitting us to provide a javelin having a hand grip large enough to be more readily gripped by the athlete with a large hand. During the cutting operation the laminated splints 10 and 11 are trimmed and finished to conform with the desired outside taper of the javelin at the forward end and the trailing ends of the pieces 6 and 7 are smoothed out into a uniformly decreasing taper.

When the javelin has been shaped properly it is fitted to a metallic pointed ferrule of the conventional type that has been heated sufficiently to expand the bore 4 and when the wood has been inserted and the ferrule 3 permitted to contract, the ferrule closely grips and adheres to the forward end of the shaft.

As shown in Figure 9 the shaft halves 6' and 7' and forward ends are provided with a slightly greater tapering surface back to a point at which the wrapping for the hand grip is to start. An

abrupt shoulder is provided and the material reduced to the required diameter to provide the correct sized hand grip and the wrappings 13 are then made. In this manner it is possible to streamline the javelin and eliminate the resistance that is normally present when the grip 5 is completely exposed. This streamlining is not possible except when wood of the characteristics described above is used, together with the interior opening which we embody in our javelin. 10

By our construction we are able to manufacture a javelin embodying the principles of strength inherent with tubes and the like, and of a sufficient large diameter throughout its length to increase rigidity and to eliminate or reduce "whipping" or vibration. 15

It is to be understood that the form of our invention, herewith shown and described, is to be taken as a preferred example of the same, and that various changes in the shape, size and arrangement of parts may be resorted to, without departing from the spirit of our invention, or the scope of the subjoined claims. 20

Having thus fully described our invention, what we claim as new and desire to secure by Letters Patent is:

1. A javelin comprising a hollow shaft tapered at each end, formed of two or more grooved strips of wood secured together with opposed grain structure and having laminated splints secured 30 to the head end of said shaft and shaped to conform to the tapering contour of said head end, a javelin point affixed to the head end of said shaft enclosing a front portion of the shaft strips and the splints, and grip means about said shaft 35 adjacent the longitudinal center of gravity of the shaft.

2. A javelin comprising a hollow shaft fashioned of two or more strips of wood secured together with opposed grain structure, a javelin point secured to the forward end of said shaft, and grip means about said shaft adjacent the center of gravity. 40

3. A javelin comprising a hollow shaft fashioned of grooved strips of wood secured together 45 and tapered to each end, a javelin point secured to the head end of said shaft, grip means about the longitudinal central portion of said shaft, and the diameter of said shaft forward of the grip tapering from the head end to a size approximately the outside diameter of said grip to reduce wind resistance when the javelin is thrown. 50

4. A javelin comprising a hollow shaft formed of a multiple number of strips of wood secured 55 together having a counterweight pocket in the trailing end portion of said shaft, a counterweight in said pocket, a javelin point affixed to the head end of said shaft and grip means about said shaft adjacent the longitudinal center of gravity of the javelin.

5. A javelin comprising a hollow shaft tapered at both ends and formed of two or more strips of wood secured together with opposed grain structure and having laminated splints secured 65 to the head end of said shaft, a javelin point affixed to the head end of said shaft, and grip means about said shaft adjacent the longitudinal center of gravity of the javelin.

6. A javelin comprising a hollow shaft tapered 70 at both ends and formed of two or more strips of wood secured together and having laminated splints secured to the head end of said shaft, a javelin point affixed to the head end of said shaft and over a front portion of the splints, and grip 75

means about said shaft adjacent the longitudinal center of gravity of the javelin.

7. A javelin comprising a hollow shaft having closed and tapered ends, laminated splints secured to the head end of the hollow shaft, a javelin point affixed to said shaft and enclosing a portion of said splints, and grip means about said shaft adjacent the longitudinal center of gravity of the javelin.

10 8. A javelin comprising a wooden shaft formed

of a pair of strips of wood secured together with the natural grain of one strip in reverse to the natural grain of the other strip, both of said strips having been previously cut from a single blank, a javelin point attached to the forward end of said shaft, and grip means adjacent the longitudinal center of gravity of the shaft and its point.
